UNITED STATES PATENT OFFICE.

MANUEL A. T. GILLBEE, OF PHILADELPHIA, PENNSYLVANIA.

DESIGN FOR AN ARTICLE OF MANUFACTURE.

56,594.

Specification for Design.

Patented Nov. 16, 1920.

Application filed August 14, 1919. Serial No. 317,615. Term of patent 3½ years.

To all whom it may concern:

Be it known that I, MANUEL A. T. GILLBEE, a citizen of the United States, residing in Philadelphia, Pennsylvania, have invented a certain new, original, and ornamental Design for an Article of Manufacture, of which the following is a specification, reference being had to the accompanying drawing, forming part thereof, in which the figure is a face view of a card-mount showing my new design.

I also contemplate using this design in the form of book and booklet covers, picture frames, portfolios and similar articles of manufacture.

I claim:

The ornamental design for an article of manufacture, substantially as shown.

MANUEL A. T. GILLBEE.
